UNITED STATES PATENT OFFICE.

BERNARD R. DUTCHER, OF NEW YORK, N. Y., ASSIGNEE TO GRAHAM-CHISHOLM COMPANY, OF NEW YORK, N. Y., A CORPORATION OF NEW YORK.

LOOSE-LEAF BINDER.

1,403,303.

Specification of Letters Patent. Patented Jan. 10, 1922.

Application filed July 12, 1919. Serial No. 310,424.

To all whom it may concern:

Be it known that I, BERNARD R. DUTCHER, a citizen of the United States, residing in New York, in the county of New York and 5 State of New York, have invented certain new and useful Improvements in Loose-Leaf Binders, of which the following is a specification.

My present invention relates to an improvement in loose-leaf binders, the object 10 of the invention being to provide an improved universal type of post gripping device.

Another object of my invention is to provide composite binder means, which, while 15 they are separable and are economical to manufacture, may be utilized to cooperate in operative function without too much precision in the manufacture thereof.

Another object of my invention is to provide means whereby the binding posts may 20 be readily gripped and held upright in vertical position thereby obviating the skewing of one or both of the binder posts when gripping the same in the binder member.

These and other advantages will appear from the subjoined specification, and by reference to the drawings herewith, in which,—

Figure 1 is a perspective view of my device;

Figure 2 is a fragmentary longitudinal sectional view thereof;

Figure 3 is a transverse sectional view.

Figure 4 is a fragmentary plan view of 35 the locking member;

Figure 5 is a partial plan view of the complete locking element, and

Figure 6 is a side elevation thereof.

In my present type of device, I obtain an 40 improved form of binder member such as is used in loose-leaf binders, inasmuch as I have done away with two heretofore objectionable faults in this class of binder member, one of the said faults being due to the 45 fact that when binder posts are initially locked into operative position, there is a tendency for them to throw askew thereby coming out of registration with the cooperating perforations in the loose-leaf sheets 50 that are used therewith, and in the opposite binder member.

By referring to Figure 1, the binder member generally denoted by 3 is provided with

suitable orifices 4 and 5 in the outer casing thereof wherein to receive the customary 55 binding posts, 1 and 2, which are shown in dotted lines; the ends 6 and 7 of the binder member being formed so as to become closures for the binder member, thereby forming a smooth-ended device of pleasing appearance. The edges of the orifices 4 and 5 form locking shoulders against which the posts 1 and 2 are locked, as will be explained.

In the construction of my device, the casing generally denoted by 8, of the binder 65 member 3 is made preferably of rolled light gage sheet metal, and has formed therein a rectangular chamber 9 running the entire length thereof.

Into this chamber is placed a suitable 70 clamp bar 10, which is utilized for the purpose of drawing up and locking or clamping the binder posts 1 and 2 in operative position.

This clamp bar is so made that its gripping portions thereof are more or less resilient, and it is so made that the locking jaws 75 11 thereof, when the clamp bar 10 is in operative position, are constructed as to accommodate themselves to a slight variability in the registration position and diameter of 80 the members 1 and 2. This will now be more described in detail.

By referring to Figure 4, which shows one of the locking ends of my device in plan view, it will be noted that the locking jaws 85 11 are formed by two opposing members 11—11, the inner faces of which are inclined toward the center, or are angular, and that the clamp bar is slit in opposite directions as at 12 and 12' a sufficient distance away 90 from the jaw portions 9 as to allow a certain amount of give, or resiliency, to the locking faces 11. In order to accentuate this resilient or giving action of the jaws 11, I have further removed the material on either side of 95 the jaws 11 as at 13 thereby making the jaws much narrower than their normal width if they were left uncut, keeping sufficient strength therein to properly perform the duty required of them, but leaving them 100 sufficiently resilient to accommodate themselves to the usual mis-registration and varying diameter of the coacting parts as would occur in ordinary manufacture.

The foregoing is better demonstrated if we 105 refer to Figure 5 which shows specifically a

full sized clamping bar which is broken away in the middle in order to shorten the length thereof. While the discrepancies here set forth are extremely exaggerated, this is purposefully done in order to bring out the features that exist in a minor way in the article themselves.

Dimension A is the normal operative distance between the centers of the locking 10 openings 14—14 of the clamping bar, B is the functioning location of two bushing members 15—15, which will be later described, and it will be noted that the left hand bushing member 15 is well forward 15 and out of pitch, thus making a discrepancy between the two center distances A—B. It will also be noted that while the right hand bushing member 15 is in substantial contact with the jaws 11 of the bar 10, that the left 20 hand member 15 has moved forward to the left a certain distance, but is also in contact with its cooperating locking jaws 11, expanding the same out of their normal positions as may be ascertained by referring to 25 the slot 12 and comparing it with other slots 12. In other words, the two locking jaws 11 on the left hand side of the bar as shown in Figure 5 have expanded slightly in order to accommodate for the difference between the 30 centers A—B, which difference may be caused by variation in diameter of the bushings or their lack of registration or both.

The bushing members 15 are utilized for forming seat or gripping members for the 35 reception of the binder posts 1 and 2, and the bushings are of the same height as the height of the chamber 9 formed between the opposing walls of the casing 8 and are a sliding fit therebetween. Obviously when these 40 sliding bushing members are placed in the casing they cannot get out of position nor tilt, and at the same time their height forms a greater vertical gripping area or surface for engaging the binder posts members than 45 has heretofore been utilized in this kind of binder. These bushing members are loosely set into the openings 14 and are simply carried to and fro by the reciprocation of the lock bar 10 which is operated by means of 50 the usual key, not shown, and the threaded key-shank 16 which is mounted in a threaded hole in a block 17 which is riveted or otherwise affixed to the casing member 8 in the usual manner.

55 The threaded member 16 has a cylindrical head 18 thereon which fits in a suitably formed head slot 19 in one end of the lock bar 10 so that upon rotation by means of a key member 16, the block 17 being held as 60 described, the lock bar 10 is reciprocated to and fro as is customary in devices of this class.

In the manufacture of devices of this type, it is obvious that errors must occur between 65 the distances between centers A of the lock

bar 10 and the corresponding openings 4 and 5 which are located in the casing 8, all of which openings are supposed, theoretically, to coincide in such a manner as to properly engage the binding posts 8 when they are in 70 operative engagement. As a matter of fact, however, unless these members are assembled completely and all drilled together, it is seldom that there is sufficient precision registration between all of the cooperating locking openings to properly clamp the binding posts and hold them properly vertical. Where the holes 4 and 5 are placed in the casing by a separate operation and the corresponding holes 14 are placed in the bar 10 80 at different operations and when the device is assembled and in use, there is always sure to be one of the binder post members which will receive nearly all of the binding pressure and the mate binding post would receive very little due to this discrepancy or lack of registration.

By means of the foregoing description of the resilient jaw members 11 and the methods of mounting the post-engaging bushing 90 members therein, it is obvious that should the openings in the casing 8 and the lock bar member 10 be out of registration, the posts 1 and 2 may be introduced therein and when locked will be properly engaged with a gripping lock owing to the slight giving of all of the jaw members 11, each jaw member giving away slightly in accordance with its lack of registration with the corresponding locking holes 4 and 5 in the casing member 8 and any discrepancy in the diameters of the post members 1 and 2. 95

It will be obvious that the device will operate if the bushings 15 are eliminated since, in that case, the clamping will be effected on 100 the posts.

I claim:

1. A clamp bar for loose leaf binders comprising, an elongated body provided with locking openings each formed with converging locking jaws at one end, said locking jaws extending in the same direction at each opening, both of said openings each being continued at their opposite ends into aligned slits. 110

2. A clamp bar for loose leaf binders comprising, an elongated body provided with locking openings each formed with a substantially semi-circular portion at one end and converging locking jaws at the other end, said locking jaws extending in the same direction at each opening, said openings each being continued at opposite ends into aligned slits. 120

3. A clamp bar for loose leaf binders comprising an elongated body provided with locking openings each formed with a substantially semi-circular portion at one end and converging locking jaws at the other end, said locking jaws extending in the same 125 130

direction at each opening, said openings each being continued at opposite ends into alined slits, the slits at opposite ends being of unequal length with the slit extending from 5 the locking jaws longer than the slit extending from the semi-circular end.

4. In combination, a binder member provided with orifices; a clamp member having locking openings; bushings disposed in said 10 locking openings; posts passing through said bushings and orifices; and means for moving said bar into engagement with said bushings.

5. In combination, a binder member having parallel spaced walls provided with registering orifices; a clamp bar between said walls and having locking openings; locking bushings disposed in said locking openings; binder posts passing through said bushings and orifices; and means for moving said bar 20 into engagement with said bushings.

6. In combination, a hollow binder member having registering locking orifices; a clamp bar therein having locking openings approximately registering with said orifices 25 and forming converging locking jaws and dividing the bar into a pair of resilient portions carrying the jaws; locking bushings loosely disposed in said openings and engaged by said jaws; binder posts passing 30 through said bushings and orifices; and means acting on said bar for pushing said jaws into wedging engagement with said bushings.

7. In combination, a hollow binder member having parallel spaced walls provided with registering locking orifices; a clamp 35 bar between said walls and having locking openings approximately registering with said orifices and forming converging locking jaws; locking bushings larger than and approximately co-axial with said orifices and loosely disposed in said locking openings and tangentially engaged on approximately diametrically opposite sides by said converging 40 jaws; binder posts passing through said bushings, locking openings and orifices; and means acting on said bar for pushing said jaws into wedging locking engagement with said bushings.

50 8. In combination, a binder member; bushings associated therewith; binder posts disposed in said bushings; and a clamp member for locking said posts in said bushings.

9. In combination, a pair of relatively 55 movable members; bushings associated therewith; posts in said bushings and locked therein by relative movement of said members.

10. In combination, a binder member provided with orifices; locking bushings associated with said binder member; binder posts passing through said bushings and orifices; and a movable clamp member locking said posts in said bushings.

65 11. In combination, a hollow binder member provided with orifices; locking bushings

disposed in said binder member; binder posts passing through said bushings and orifices; and a clamp bar movable within said member for bringing about a locking action between said posts and bushings. 70

12. In combination, a binder member having spaced walls provided with orifices; locking bushings disposed in said binder member substantially in registration with said orifices; binder posts passing through said, 75 bushings and orifices; and a clamp bar movable between said walls for bringing about a locking action between said posts and said bushings and orifices.

13. In combination, a hollow binder member 80 having two pairs of opposed orifices alined with each other; a clamp bar disposed in said member and provided with locking openings each formed with locking jaws, both of said openings being continued at 85 their opposite ends into alined slits; and lockable elements loosely disposed in said openings and orifices and carrying separate locking portions engageable by said jaws.

14. In combination, a hollow binder member 90 having pairs of opposed locking orifices alined with each other; a clamp bar therein having locking openings approximately registering with said orifices and forming converging locking jaws and each dividing 95 a portion of the bar into a pair of resilient portions carrying the jaws; and lockable elements loosely disposed in said openings and orifices and carrying separate locking portions engaged by said jaws with a wedging 100 action.

15. In combination, a hollow binder member having pairs of opposed locking orifices 105 registering with each other; a clamp bar therein having locking openings approximately registering with said orifices and forming converging locking jaws and each dividing a portion of the bar into a pair of resilient portions carrying the jaws; lockable elements loosely disposed in said openings and orifices and carrying locking portions engaged by said jaws; and means acting 110 on the bar for moving said jaws into wedging engagement with said portions.

16. In combination, a hollow binder member having pairs of opposed orifices alined with each other; a clamp bar disposed in said member and provided with locking openings each formed with converging locking jaws at one end, said locking jaws extending in the same direction at each opening, both of said openings being continued at their opposite ends into alined slits; and lockable elements loosely disposed in said openings and orifices and carrying locking 120 parts engageable by said jaws with a wedging engagement.

17. In combination, a hollow binder member having pairs of opposed orifices alined with each other; a clamp bar disposed in 125

said member and provided with locking openings each formed with converging locking jaws at one end, said locking jaws extending in the same direction at each opening, both of said openings being continued at their opposite ends into aligned slits; lockable elements loosely disposed in said open-

ings and orifices; and means acting on the bar to cause the locking of the elements by a wedging action of the jaws.
